UNITED STATES PATENT OFFICE.

ORA J. HEATH, OF SPRINGFIELD, OHIO.

WINDOW-FIXTURE.

1,111,067.

Specification of Letters Patent. Patented Sept. 22, 1914.

Application filed December 8, 1913. Serial No. 305,383.

To all whom it may concern:

Be it known that I, ORA J. HEATH, a citizen of the United States, residing at Springfield, in the county of Clark and State of Ohio, have invented certain new and useful 5 Improvements in Window-Fixtures, of which the following is a specification, reference being had to the accompanying drawings.

10 This invention relates to new and useful improvements in window fixtures and more particularly to a combined curtain pole and shade roller support.

The main object of the present invention 15 is the provision of a device of the above character wherein the shade roller and the curtain pole are so mounted that they may be relatively adjusted vertically with respect to each other so that either the shade roller 20 or the curtain pole supporting member may be adjusted independently of each other.

Another object of the present invention is to provide an adjustable combined support of the above character which can be quickly 25 and readily secured to a window casing or removed therefrom.

A further object of the invention is the provision of a device of the above character which will possess advantages in points of 30 efficiency and durability, is inexpensive to manufacture and at the same time is simple in construction and operation.

With the above and other objects in view, the invention consists in the novel features 35 of construction and the combination and arrangement of parts to be hereinafter more fully described, pointed out in the claims and shown in the accompanying drawings, in which—

40 Figure 1 is a side elevation of a combination bracket constructed in accordance with my invention; Fig. 2 is a front elevation; Fig. 3 is a transverse sectional view taken on the line 3—3 of Fig. 1; and 45 Fig. 4 is a detail elevation of the supporting member opposite to that illustrated in Fig. 1.

In carrying out my invention, I provide a substantially U-shaped bracket 1 which is to be formed of sheet metal preferably of brass, 50 but it will be understood that any other suitable material may be used. One end of the bracket, which is preferably the upper end, is provided with an inwardly projecting spur 2 adapted for engagement with the upper edge of the window casing to securely hold this end of the bracket in position.

Formed on the lowermost end of the bracket is an outwardly projecting perforated flange 3 which is secured to the outer face of the window casing by means of a screw, as indicated at 4. It will be understood that any suitable fastening means may be used other than the screw illustrated in the accompanying drawings.

The bracket 1 forms the main support for my device and one of the brackets is to be arranged upon each side of the window and mounted within the body of the bracket and adapted for lateral adjustment is an upright supporting member 5. One of the 60 supporting members 5 is provided with a plurality of spaced circular openings 6 having elongated recesses 7 communicating therewith which are adapted to receive one of the spindles of the shade roller 8, the other of said supporting members is provided with a plurality of spaced circular openings 9 adapted to receive the other spindle of the roller 8 and is adapted to rotate within said openings. The upper and lower 65 end portions of the bracket 1 are provided with elongated slots 10 in which the bolts 11 are movable. The bolts 11 are carried by the outwardly projecting flanges 12 of the supporting members 5 and are adapted to project out through the slots 10. Winged nuts 13 are threaded upon the outer ends of the bolts 11 and are adapted for frictional engagement with the end portions of the bracket 1 to securely retain the supporting 70 members 5 in various adjusted positions with respect to the window casing.

It will be noted that by having the spaced supporting members 5 provided with the openings 6 and 9, the shade roller 8 may be 75 vertically adjusted and arranged to any desired height and it may also be adjusted laterally with respect to the window casing. The body portion of the bracket 1 is provided with an elongated slot 14 in which is 80 adapted to work the bolt 15. Mounted upon the bolt 15 and adapted to be adjusted vertically with respect to the bracket 1 is the curtain pole support 16, said support being 85 adjusted vertically with respect to the bracket 1 and retained in any desired position by means of the winged nut 17 which is threaded upon the bolt 15 and is adapted to tighten the vertical portion of the curtain support against the bracket 1 so as to securely retain the same in various adjusted 90 positions.

The curtain pole support comprises an arcuate body portion formed of flat sheet metal and of any desired size. Formed integral with one end of the body is the vertically projecting supporting member 18 which is mounted upon the outer end of the bolt 15 for adjustment and is to be securely held in various adjusted positions by means of the nut 17. From this it will be apparent that the curtain pole supporting member may be adjusted to any relative position with respect to the bracket 1 and securely held in such position. From the foregoing description taken in connection with the accompanying drawings, it will be readily apparent that I have provided a simple and durable device of the above character which can be quickly and readily secured to the window casing or removed therefrom and wherein the shade roller and the curtain pole support may be readily adjusted vertically with respect to the supporting bracket. It will also be apparent that my improved device is extremely simple in construction and can be manufactured and placed upon the market at a comparatively small cost.

While I have shown and described the preferred form of my invention, it will be obvious that various changes in the details of construction and in the proportions may be resorted to for successfully carrying my invention into practice without sacrificing any of the novel features or departing from the scope of the appended claims.

What I claim is:—

1. A device of the class described including a substantially U-shaped bracket, having a spur member at one end and an outwardly projecting perforated flange at the other end, a supporting member adjustably mounted within the bracket and a second supporting member adjustably mounted upon the body of the bracket.
- 45 2. A device of the class described including a U-shaped bracket having an elongated

slot formed in the end portions thereof, a supporting member having outwardly projecting perforated flanges and adjusting bolts carried by said flanges and adapted to be movably arranged within said slots, as and for the purpose set forth.

3. A device of the class described including a U-shaped bracket having an elongated slot formed in the end portions thereof, a supporting member having outwardly projecting perforated flanges and adjusting bolts carried by said flanges and adapted to be movably arranged within said slots, said supporting member being provided with suitable bearings for the spindles of a shade roller and a second supporting member adjustably mounted upon the body of the bracket.

4. A device of the class described including a U-shaped bracket having its ends removably secured to a window casing and having its body portion provided with a vertically disposed elongated slot, a curtain pole supporting member, and a bolt carried by said supporting member and adapted to be adjustably disposed within said slot, as and for the purpose set forth.

5. A device of the class described including a U-shaped bracket having its ends removably secured to the window casing, said end portions having elongated slots therein, supporting members having outwardly projecting flanges, bolts carried thereby and adjustably arranged within said slots, the body portion of said bracket being provided with an elongated slot, a curtain pole supporting member, a bolt carried thereby and adjustably mounted within said slot, as and for the purpose set forth.

In testimony whereof I hereunto affix my signature in the presence of two witnesses.

ORA J. HEATH.
